UNITED STATES PATENT OFFICE.

PAUL W. STANKEE, OF DAVENPORT, IOWA.

HOG-FARROWING GUARD-RAIL.

1,318,815.

specification of Letters Patent.

Patented Oct. 14, 1919.

Application filed December 19, 1918. Serial No. 267,510.

To all whom it may concern:

Be it known that I, PAUL W. STANKEE, a citizen of the United States, residing at Davenport, in the county of Scott and State 5 of Iowa, have invented certain new and useful Improvements in Hog-Farrowing Guard-Rails, of which the following is a specification.

This invention relates to guard rails for 10 hog pens, designed particularly to provide means whereby crushing of pigs by the mother hog against the walls of the pen will be obviated.

The primary object of the invention is to 15 provide a guard rail of simple and improved construction which shall be strong and durable so as not to be broken or rendered useless by the mother hog, and which may be easily and quickly folded against the side 20 wall of the pen in order that the area of the pen may be increased if desired.

A further object is to provide guard rails upon the dividing partitions of the pen of such character and construction that the 25 said partitions may be removed easily and stored or piled compactly one upon the other.

A still further object is to provide guard rails of such character that the same when 30 in operative position may be used to support the dividing partitions in proper vertical adjustment.

With these objects in view, together with others which will appear as the description proceeds, the invention resides in the novel 35 construction, combination and arrangement of parts, all as will be described more fully hereinafter, illustrated in the drawings, and particularly pointed out in the claim.

In the drawings:

40 Figure 1, is a plan view of a conventional pig pen and illustrating the application of guard rails constructed and arranged in accordance with the invention,

Fig. 2, is an enlarged sectional view taken 45 through one of the guard rails and its supporting base, and

Fig. 3, is a front elevation of a part of one of the rails.

Referring now more particularly to the 50 drawings, 4 indicates the side walls of a conventional hog pen, and 5 the end wall of the pen. The pen in the present instance is of that type wherein partitions 6 are used to provide compartments to be occupied by 55 hogs or pigs which it is desired to keep

separated, only one of such partitions or dividing walls being shown.

The guard rails are indicated at 7, and comprise stout timbers or beams of suitable material of any desired thickness and 60 breadth. These beams may be formed of planking, and it is desired that the same when in operative position be spaced about eight inches above the floor of the pen.

Arranged in spaced relation upon the inner walls of the pen, as well as upon the opposing faces of the dividing walls, are supporting brackets in the form of angle plates 8, the same being disposed vertically. 65 These plates are secured in proper position 70 in any preferred manner, and each has pivoted near its upper end a link 9, the pivots for the links being indicated at 10. It is observed that these pivots are disposed upon the plates near the bases of the same. Each 75 plate or bracket has also pivoted thereto one end of a second link 11, the pivots for the same being indicated at 12. These second links are pivoted to the angle plates below the pivots of the links 9 and near the outer 80 edges of the said plates.

The lower ends of the links are pivotally connected to the upwardly extending portion of an angle plate 13 secured to the upper face of the guard rail 7, and these 85 angle plates are disposed laterally of the said rails. The lower end of link 9 is pivoted as at 14 to the upstanding portion of the plate 13 near the outer end thereof, while the lower end of link 11 is pivoted to the 90 said plate at 15 near the inner end. It is observed that the pivotal connection of the link 11 with the plate 13 is below the plane of pivot 14. By connecting the links 9—11 with the plates 8—13 in the manner shown 95 and described, it is obvious that the guard rails 7 may be easily swung upwardly to the position indicated by dotted lines in Fig. 2, and when in such position the pivots 14—15 will assume a position slightly beyond the vertical plane of the pivots 10—12. This particular arrangement enables the rails to remain in upright position and the weight of the rails will be equally distributed to the plates 8—13 through the 105 pivots 10—14—12—15.

To assist in retaining the guard rails in raised position, spring catches 16 are provided. These catches are secured at one end to supporting blocks 17 fastened to the walls 110

- of the pen in such position that the free ends of the catches will snap over the forward edges of the guard rails when the latter are in upright position.
- 5 From the foregoing it is obvious that the rails 7 when lowered or swung to horizontal position will project into the pen the proper distance above the floor of the pen, and it will therefore be impossible for the mother hog in lying down to mash the pigs, either against the floor or the wall. Should it be desired to increase the area of the pen the various rails may be grasped and swung upward to the position shown in dotted lines in Fig. 2. The end of each catch will snap over the free edge of its respective guard rail and the latter will be securely held in raised position. The free edges of the said rails are provided with a protecting strip 18, to prevent the hogs or pigs being injured by splinters and to prevent the rails from becoming worn or chafed.

With reference to Fig. 1, it is observed that the adjacent ends of the rails carried

Copies of this patent may be obtained for five cents each, by addressing the "Commissioner of Patents, Washington, D. C."

by the side 4 of the pen are spaced apart 25 a distance such as will permit of the partition or dividing wall being easily removed, and these ends will assist in securing and steadyng the partition when the latter is in place.

30 While the above is a description of the preferred embodiment of the invention, it is obvious that changes in the details may be resorted to without departing from the invention as defined by the claim.

35 What is claimed is:

A guard structure comprising a support, plates attached thereto, relatively short links pivoted to the plates, relatively long links pivoted to the plates at points above 40 the pivot points of the short links and beyond the rear vertical side thereof, other plates pivotally connected with the short and long links and located between them, and a guard rail attached to the last men- 45 tioned plates.

In testimony whereof I affix my signature.

PAUL W. STANKEE.
